UNITED STATES PATENT OFFICE.

PHILIP VAN BIBBER NEBERGALL, OF LA GRANDE, OREGON, ASSIGNOR OF ONE-HALF TO
CLINTON W. VAN FLEET, OF LA GRANDE, OREGON.

PRINTING ATTACHMENT FOR PAPER HOLDERS AND CUTTERS.

1,330,386.

Specification of Letters Patent. Patented Feb. 10, 1920.

Application filed June 27, 1918. Serial No. 242,244.

To all whom it may concern:

Be it known that I, PHILIP V. B. NEBERGALL, a citizen of the United States, and a resident of La Grande, in the county of Union and State of Oregon, have made certain new and useful Improvements in Printing Attachments for Paper Holders and Cutters, of which the following is a specification.

10 My present invention relates generally to the holders for rolls of wrapping paper and the like, and particularly to printing attachments therefor by which the paper web will receive impressions at equi-distantly spaced points in its length, as it is pulled from the roll, and the primary object of my invention is the provision of a simple inexpensive attachment for the cutting frames of roll holders by means of which the paper web may be printed upon its inner or lower surface, so that it will be ready for instant use when severed without the necessity of reversing the severed strip, as usual.

25 In the accompanying drawings which illustrate my present invention:—

Figure 1 is a front elevation illustrating the practical application of my invention;

Fig. 2 is a side elevation, and,

Fig. 3 is a vertical transverse section.

30 Referring now to these figures, I have indicated the stand or frame 10 as supporting a roll of wrapping paper 11, and in connection with a downwardly curved rectangular frame 12 secured to and extending from one side of the frame 10 and supporting a cutter 13 at its lower outer end, against which the web 14 from the roll 11 is moved, in order to sever the desired length thereof, after it has been pulled from the roll. For this 40 purpose the cutter supporting frame 12 has a lower rectangular guide frame 15, terminating at its lower end in a swinging loop 16, through which the free end of the web 14 is extended, so that when pulled out it 45 may be readily drawn against the cutter, and the free end of the integral portion of the web will remain in position to be readily grasped when another section of the web is to be drawn off and severed.

50 In connection with such a device my present invention proposes a printing attachment having a supporting frame, consisting of side bars 17 secured at their upper ends to cross pieces 18, in turn secured to the 55 sides of the cutter frame 12, as seen in Fig.

1. These side plates 17 receive the trunnions of a printing roller 19 adajacent their upper ends, this printing roller having a peripheral printing die 20, and being so disposed as to receive the web 14 around the 60 upper portion thereof. The side plates 17 also receive the end trunnions of a pair of rollers 21 and 22, the latter of which have their trunnions disposed in slots 23 of the side plates and engaged by springs 24 in order to press the peripheries of these rollers, covered with any suitable soft absorbent material, into engagement with one another and into engagement with the surface of the printing roller 19, these rollers being 65 adapted to receive and hold a supply of ink for the printing roller, and being covered by a shield 25 which extends over the same between the side plates 17, and effectively prevents contact of the web 14 therewith. 70 In its passage downwardly around the upper portion of the printing roller 19, the web 14 is engaged by a soft covered pressure roll 26, whose trunnions are slidably disposed in vertical slots 27 of down-turned side ears 80 28 of a supporting bracket 29, attached to another cross bar 30 of the cutter frame 12, the trunnion of the said roller 26 being engaged by springs 31, which serve to press the roller 26 downwardly, and snugly into 85 engagement with the web 14, so as to force the latter in firm even contact with the printing die 20, as the web moves, and in this way provide for a clean clear cut impression, irrespective of creases, folds or other slight 90 imperfections in the paper web, which are of course to be encountered in the majority of paper rolls of this nature.

My invention is thus particularly effective for the purposes set forth and may be readily mounted to operate as described with little expense either in first cost or up-keep.

I claim:—

95 In a device of the character described, is a printing roller having a peripheral die 100 arranged to receive a web downwardly over the upper portion thereof, a pair of inclined side brackets in the upper rear portions of which said printing roller is journaled, a pair of inking rollers in peripheral contact 105 with one another and one of which engages the lower forward portion of the printing roller, said inking rollers being journaled in the lower forward portions of the said side brackets and one of the said inking rollers 110

having movement in the brackets toward the other roller, springs engaging and controlling the last mentioned roller, a shield connecting the lower forward portions of the 5 said brackets and extending over the two inking rollers below the printing roller, a bracket mounted at the rear of, and above the printing roller and having depending

side ears at its upper forward portion above the printing roller provided with vertical 10 slots, and a spring controlled pressure roller journaled in movable relation in the slots of said side ears to engage the upper portion of the printing roller as and for the purpose set forth.

PHILIP VAN BIBBER NEBERGALL
